UNITED STATES PATENT OFFICE.

THOMAS C. WRIGHT, OF GOLDFIELD, NEVADA.

HOISTING AND DUMPING APPARATUS.

No. 929,530.

Specification of Letters Patent. Patented July 27, 1909.

Application filed January 13, 1909. Serial No. 472,001.

To all whom it may concern:

Be it known that I, THOMAS C. WRIGHT, a citizen of the United States, residing at Goldfield, in the county of Esmeralda and 5 State of Nevada, have invented new and useful Improvements in Hoisting and Dumping Apparatus, of which the following is a specification.

My invention relates to hoisting apparatuses for mining shafts, or the like, and particularly relates to that class of hoists in which a bucket may be made to dump at any desirable level.

The particular object of the invention is 15 to provide a hoisting apparatus in which a mining bucket or the like may be hoisted to any suitable level and conveniently dumped.

The invention is also applicable for use in the construction of tall buildings, where the 20 bucket may be hoisted to any of the floor levels, stopped and dumped. And an important object is the provision of means whereby the bucket may be dumped in either direction.

25 A further object of the device is to provide a means whereby a bucket may be readily detached from its hauling cable, and quickly attached thereto again when required.

30 Other objects will become manifest in the following specification.

The invention consists of the parts and the construction and combination of parts, or their equivalents, as set forth in the following specification, and shown in the accompanying drawings, in which—

Figure 1 is a front elevation of the bucket and frame. Fig. 2 is a similar view of the lower end of the frame. Fig. 3 is a transverse section on line X—X of Fig. 2. Fig. 4 is a detail section showing the stop and trip mechanism. Fig. 5 is a perspective view of one of the bucket carriers.

I have shown the invention applied especially in conjunction with the head frame A of a mining shaft, although obviously such a frame may be used in the erection of tall buildings, between the vertical studs of which is slidably mounted a cross-head 2 45 provided with suitable runners 3 adapted to engage slides 4 by which the cross-head is guided. The hoisting cable 5 passes through a removable wearing-block 6 in the cross-head and connects by a swivel hook 7 to the 50 bail of the bucket 8.

Pivotal or otherwise suitably connected

with the cross-head are a pair of spring-actuated arms 9 which extend downward at each side below the cross-head and are provided with side flanges which slidably embrace the guides 4 of the frame; the springs 10 acting to press the arms outward always against the guides when the arms are engaged with the guides, and to carry the lower ends of the arms into the depressions 60 or recesses 11 formed at any suitable point in the guides. The lower ends of the spring-actuated arms 9 carry suitable hangers or 65 bearing members 12 which are designed to be pressed inward toward the bucket and 70 engage suitable lugs or pintles 13 thereon whenever the bucket is raised to a point so that an adjustable clamp member 14 on the cable lifts the cross-head and carries the lower ends of the arms 9 out of the notches 75 11. Ordinarily when the bucket is lowered for filling or loading, the cross-head is supported by reason of the engagement of the lower ends of the spring-actuated arms 9 against the bottom ledge of the notch 11, as 80 shown in Fig. 2; the cable and bucket having thus a movement independent of the cross-head. The guides 4 may be of any suitable length, and the cross-head, with the releasing notches 11, may be placed at any 85 desired point in the mine or elevator well.

In operation, with the cross-head supported in the notches 11, as shown in Fig. 2, the bucket after being filled is raised until the bottom of the bucket comes opposite the 90 hangers 12, with the pintles 13 in the plane of the hangers in such position that when the hangers are pressed in they will inclose the pintles, as shown in Fig. 1. In order to assist in positioning the pintles with respect to 95 the hangers, I provide suitable guides, as shown at 15, arranged contiguous to the depressions 11 and on each side of the guides 4, which guides are so flared and fashioned that when the operator swings the bucket around 100 so that the pintles pass in between the guides, these pintles will be in the same plane with the hangers 12. The clamp 14 on the cable is so adjusted that it will engage the under side of the cross-head when the 105 pintles on the bucket are opposite and in the plane of the hangers 12. A further hoisting of the cable 5 carries the cross-head upward with the bucket, and as the cross-head rises, the lower ends of the arms 9 are drawn out of the notches 11 and the hangers are pressed 110 in toward the bucket until the hangers em-

brace the opposite sides of the pintles and are in a position to support the bucket and its load whenever the cable is slackened up and a suitable stop mechanism, such as is shown in Fig. 4, is interposed in the path of the arms to support the cross-head and its load independent of the cable. This supporting or catch mechanism of Fig. 4, while embodied in a separate application, comprises a pivoted stop member 18 and a releasing dog or trip 19, with suitable means, as a sliding weight 20, to carry the trip 19 normally outward into the path of the cross-head and sliding arms 9. The stop catch 18, trip 19 and weight 20 are suitably housed in a guide 4; it being understood that each guide is provided with a corresponding catch mechanism. The stop catch 18 and trip member 19 are weighted so that they project normally into the path of the cross-head and sliding arms; the outward movement of the stop member 18 being limited by the bottom of the slot in the guide in which the member 18 moves. The trip member 19 is so positioned that it may swing upwardly without interfering with, or acting on, the catch 18, but when pushed down it will engage a projection 21 on the stop member 18 and carry the latter back within its housing, leaving the cross-head and arms free to move. Downward movement of the weight 20 is limited by a suitable stop, as 22, formed by a shoulder in the housing, which will permit a free upward movement of the trip 19 into the housing, as represented in dotted lines, Fig. 4; this trip being normally supported by means of the weight 20 in the path of the cross-head and sliding arms.

In operation, assuming the parts to be in the position shown in Fig. 2, with the cross-head supported by reason of the expansion of the arms 9 into the notches 11, the bucket is lowered to any suitable point and filled or loaded, and then hoisted. As the bucket approaches the guides 15 the operator turns the bucket so that the pintles 13 will engage between the guides 15, which latter will extend upward a sufficient distance to insure the proper reception of the pintles into the hangers 12. The interception of the cross-head by the clamp 14 on the cable causes the cross-head to move up with the bucket, and the contracting action of the guides 4 as the lower ends of the sliding arms pass out of the notches 11 causes the hangers 12 to embrace the pintles in the manner hereinbefore described. The upward movement of the carriage and bucket is continued until the lower ends of the arms 9 pass the stop members 18, but without allowing the trips 19 to drop below the arms. The cable is then slackened and the cross-head allowed to rest on the stops 18. The further slackening of the cable effects the dumping of the bucket, the dump being made in either direction by the operator ap-

plying a tilting pressure upon one side or the other of the bucket. This is an important advantage in mining operations, especially as it permits the dumping of selected ore upon one side of the head of the shaft into suitable cars, to be conducted to the mill, or upon the opposite side of the shaft when waste is to be dumped. By this arrangement a simple means is afforded for the separate distribution of the worthless material, and the valuable ore. When the bucket is to be lowered again, the cable is hoisted to carry the cross-head and bucket farther upward so as to release the trip 19 and allow it to drop down to the full line position of Fig. 4; and then lowering the cross-head and bucket, the trips are pressed downward, carrying the stop members 18 backward to dotted line position, Fig. 4, and out of interference with the dumping apparatus. The cross-head and arms slide down the guides 4 until the lower ends of the arms spring out into the recesses 11 and release the bucket pintles, whereon the cross-head is supported stationary, while the bucket is allowed to descend. Manifestly, as many sets of stops 18 and trips 19 may be employed, in the length of the frame, as desired, according to the level, or different points where a dump is to be made; it only being necessary to provide suitable recesses 11 where the bucket is to be picked up by the hangers, and blocking up any other recesses that may have been made, flush with the guide rails 4.

When desiring to utilize the bucket as a skip, it is unnecessary to provide the guides 4 with recesses for releasing the hangers 12 from the pintles 13, and the extensions or arms 9 would preferably be rigidly secured to the cross-head 2. The pintles 13 could be simply journaled in the hangers 12, and the clamp 14 removed from the rope 5, since the cross-head would be operable through the journaled pintles 13. The same advantages in stopping at required elevations and in double side discharging would still be retained.

Having thus described my invention, what I claim and desire to secure by Letters Patent is—

1. In a dumping device, a suitably guided, movable cross-head, a cable, a bucket on the cable, means on the cable engaging the cross-head to move the latter in unison with the cable, supporting members on the cross-head engageable and disengageable with the bucket, means for supporting the cross-head independent of the cable when said bucket-supporting means are disengaged from the bucket, and other means for supporting the cross-head independent of the cable when said bucket-supporting means are engaged with the bucket.

2. In a dumping device, a suitably guided, movable cross-head, a cable, a bucket on the

cable, means on the cable engaging the cross-head to move the latter in unison with the cable, supporting members on the cross-head engageable and disengageable with the bucket, means for supporting the cross-head independent of the cable when said bucket-supporting means are disengaged from the bucket, and other means for supporting the cross-head independent of the cable when 5 said bucket-supporting means are engaged with the bucket, said bucket-supporting means on the cross-head comprising spring-actuated arms with hangers, and the bucket having pintles engageable and disengageable 10 with said hangers.

3. In a dumping device, a suitably guided, movable cross-head, a cable, a bucket on the cable, means on the cable engaging the cross-head to move the latter in unison with the 20 cable, supporting members on the cross-head engageable and disengageable with the bucket, means for supporting the cross-head independent of the cable when said bucket-supporting means are disengaged from the bucket, and other means for supporting the 25 cross-head independent of the cable when said bucket-supporting means are engaged with the bucket, said bucket having a pivotal movement in either direction on said 30 bucket-supporting means on the cross-head.

4. The combination with suitable cross-head guides, of a cross-head sliding on said guides, a hoisting cable passing through the cross-head and having a limited movement 35 independent of the cross-head, a bucket on the cable, spring-actuated arms on the cross-head engaging said guides, said guides having opposed bucket-supporting hangers, means for moving these hangers toward and 40 from each other to engage and disengage the bucket, means for supporting the cross-head when the hangers are disengaged from the bucket, and other means for supporting the cross-head when the hangers are engaged 45 with the bucket.

5. The combination with suitable cross-head guides, of a cross-head slid able thereon, spring-actuated arms on the cross-head engaging the guides, said guides having burden-

supporting means movable toward and from each other, means for moving said burden-supporting means toward and from each other, a hoisting cable, a burden carrier on the cable, means for supporting the cross-head independent of the cable when said burden-supporting means are moved outward, means on the cable to engage the cross-head to cause the latter to have a limited movement in unison with the cable and burden carrier, means on the burden carrier engageable by said burden-supporting means on the arms when the latter are moved inwardly, and other means for supporting the cross-head when said burden-supporting means are moved inwardly. 60

6. The combination of suitable cross-head guides, a cross-head slid able thereon, spring-actuated arms carried by the cross-head and slid able on the guides, a cable passing through the cross-head, a bucket on the cable, pintles on the bucket and bucket hangers on the arms engageable and disengageable with the pintles, means for supporting the cross-head independent of the cable at different points in the length of said guides, 70 and means for engaging and disengaging said pintles with said hanger. 75

7. The combination of suitable cross-head guides, a cross-head slid able thereon, spring-actuated arms carried by the cross-head and slid able on the guides, a cable passing through the cross-head, a bucket on the cable, pintles on the bucket and bucket hangers on the arms engageable and disengageable with the pintles, means for supporting the cross-head independent of the cable at different points in the length of said guides, 80 and means for engaging and disengaging said pintles with said hangers, said last-named means provided by forming recesses in the 85 guides. 90

In testimony whereof I have hereunto set my hand in presence of two subscribing witnesses.
